OZONE APPARATUS

Application filed October 4, 1926. Serial No. 139,415.

This invention relates to apparatus for the production of ozone or ozonized air and has for its objects a simplified construction of such apparatus as well as increased efficiency.

5 In the drawings hereto Fig. 1 is a vertical section through my apparatus as taken along the line 1—1 of Fig. 2. Fig. 2 is a plan section as taken along the line 2—2 of Fig. 1. Fig. 3 is an enlarged broken section of the 10 lower corner of Fig. 2 as taken along the line 3—3 thereof, while Fig. 4 is a separate plan view of one of the separating blocks of the device.

In further detail the drawing shows an 15 iron box 1 provided with a removable lid 2 held on as by screws 3 and preferably fitted with a thin gasket along the parting line to make it tight.

This box is provided with a sheet metal 20 partition 4 forming two unequal size spaces within the box and the partition is perforated with fine holes over its entire surface.

At the bottom of the box to the right of the partition is a threaded pipe inlet 5, and 25 at the top to the left of the partition is a threaded pipe outlet 6. Within and secured to the two vertical sides of the box are angles 7, and in the space between these angles and the partition 4 the box is filled with alternating plates of metal 8 and glass 9 supported 30 on a sheet of soft rubber 10 or other dielectric at the bottom and covered by a similar sheet 11 on top of the stack and against which top sheet the lid 2 clamps, the whole stack being 35 freely removable through the top of the box when the lid is removed.

The metal sheets are of light gage bent to zigzag shape to form a corrugated plate substantially as shown. (In practice 20 gage 40 galvanized iron bent to form a corrugation of about $\frac{1}{16}$ inch deep gave good results when interposed between sheets of 20 ounce glass.)

The metal sheets are laid between the glass 45 sheets with channels running at right angles to the screen 4 and are held in place spaced from the sides of the box by cut out or L shaped blocks of wood 13 (see Fig. 4) lying against opposite sides of the box. These 50 strips of wood are of no greater thickness

than the height of the corrugations of the metal sheets and are well soaked in hot paraffine before assembling, tho if desired hard rubber or other dielectric strips may be used in place of wood.

55 Every other metal plate of the pile is provided with an electric lead 14 connected to a negative terminal 15 suitably mounted on insulators and projecting out of the box, while the alternate metal plates are similarly 60 wired at 16 to a positive pole 17.

By the arrangement described a blast of dry air forced into pipe 5 will flow through the screen and the corrugation channels of the plates for exit from the pipe 6.

65 By having the perforations in the screen small in proportion to the air pressure introduced as is intended, a pressure zone will be built up in the compartment A insuring an even flow throughout the plates. The plates are energized with a high tension A. C. current while the air pressure is applied.

70 Such an apparatus has been found to require no cooling, probably due to the large amount of air forced evenly through every part thereof, as against the amount which might be drawn therethrough by suction, and is found to give an unusually high concentration of ozone.

75 I claim:

1. Ozone apparatus comprising a box with a removable lid, an air inlet at one end and air outlet at the other end, a stack of alternating dielectric and corrugated metal plates in the box spaced from its ends, said metal plates being smaller than the dielectric plates and spaced from the sides of the box by corner-engaging insulating strips lying in the plane of the corrugated plates.

80 2. Ozone apparatus comprising a box with a removable lid, an air inlet at one end and air outlet at the other end, a stack of alternating dielectric and corrugated metal plates in the box spaced from its ends, a sheet of soft rubber covering the top and bottom of the stack, and a lid on the box clamping the stack tightly between the soft rubber sheets.

85 3. Ozone apparatus comprising a box with a removable lid, an air inlet at one end and 90

air outlet at the other end, a stack of alternating dielectric and corrugated metal plates in the box spaced from its ends, a layer of resilient material covering the top and bottom of the stack, and a lid on the box clamping the stack tightly between said resilient material.

THOMAS W. W. FORREST.
